H. HAMPER.
Means for Cleansing the Meshes of Bolting Screens.
No. 229,121. Patented June 22, 1880.

UNITED STATES PATENT OFFICE.

HENRY HAMPER, OF PLYMOUTH, MICHIGAN, ASSIGNOR TO HUNTLEY,
HOLCOMB & HEINE, OF SILVER CREEK, NEW YORK.

MEANS FOR CLEANSING THE MESHES OF BOLTING-SCREENS.

SPECIFICATION forming part of Letters Patent No. 229,121, dated June 22, 1880.

Application filed June 21, 1879.

To all whom it may concern:

Be it known that I, HENRY HAMPER, of 5
Plymouth, in the county of Wayne and State
of Michigan, have invented new and useful
Improvements in Means for Cleansing the
Meshes of Bolting-Screens, of which the fol-
lowing is a specification, reference being had
to the accompanying drawings.

My invention relates to a device for jarring
10 or agitating the bolting-cloth of the vibrating
screens in middlings-purifiers and other
machines, so as to prevent the meshes thereof
from clogging or filling up.

Previous to my invention these vibrating
15 screens have been provided with various me-
chanical devices—for instance, brushes, knock-
ers, and air-blasts—for keeping the meshes of
the bolting-cloth open; but these devices are
20 more or less objectionable on account of their
expense and their liability of getting out of
order.

The object of my invention is to provide a
simple and cheap device for accomplishing the
desired result; and my invention consists of
25 loose balls passed back and forth over the sur-
face of the bolting-cloth by the motion of the
vibrating screen, as will be hereinafter fully
set forth.

In the accompanying drawings, Figure 1 is
30 a sectional elevation of a shaking sieve pro-
vided with my improvement, and Fig. 2 is a
perspective view thereof.

Like letters of reference designate like parts
in both of the figures.

35 A represents the rectangular screen-frame;
B, the bolting-cloth, and c one or more longi-
tudinal stiffening-bars connecting the head
and tail pieces of the screen-frame.

40 d are the lower cross-bars, which support
the bolting-cloth, and e the upper cross-bars,
connecting the longitudinal bar c with the
side pieces of the screen-frame, and arranged
sufficiently above the bolting-cloth to allow
the material to freely pass under them.

45 A vibratory or reciprocating motion is im-
parted to the screen by any common and well-
known mechanism.

f represents loose balls, preferably con-

structed of rubber or other elastic material,
and placed upon the bolting-cloth within each 50
of the compartments formed by the screen-
frame and its longitudinal and cross pieces c e.

The screen-frame is slightly inclined toward
its tail end, or hung so that its vibratory mo-
tion will impel the material toward the tail 55
end in the usual manner.

The movement of the screen causes the
balls f to pass over the bolting-cloth in a pecu-
liar dancing or jumping motion in the direc- 60
tion in which the material moves over the
same until the balls strike against the tail-
board of the compartment in which they are
contained, when the impact will return the
balls at once to the opposite end of the com- 65
partment. In this manner the balls are caused
to pass backward and forward over the bolting-
surface, whereby the latter is continually
jarred or agitated and its meshes prevented
from filling up.

When non-elastic balls are employed the 70
requisite elasticity may be obtained by lining
the tail end of each frame-compartment with
a material possessing sufficient elasticity to
return the balls by this impact to the head of
the compartment.

75 My improved means for clearing the meshes
of the bolting-cloth is very simple and cheap,
entirely noiseless in its operation, and not lia-
ble to get out of order.

If any particular portion of the screen is 80
more liable to become clogged than other por-
tions a greater number of balls may be placed
in the compartments over such portion of the
screen, thus enabling the attendant to regu-
late the jarring action in accordance with the 85
requirements of the various sections or por-
tions of the screen.

I claim as my invention—

1. The combination, with a shaking screen
provided with open pockets or compartments, 90
of loose balls placed in said compartments,
and confined thereby to certain portions of
the screen, whereby each ball is caused to
pass back and forth over that portion of the
screen only which is inclosed by the compart- 95
ment in which the ball is contained, and the
